COMBINATION REPAIR HEEL

Silvio Nenni, Kingston, N. Y.

Application March 3, 1938, Serial No. 193,751

3 Claims. (Cl. 36—35)

My invention relates generally to repair heels or lifts, and particularly to a replacement rubber heel for use in the shoe repairing trade especially for the reconditioning of the heels of ladies' shoes, 5 and an important object of my invention is to provide a combination repair heel of this character which is so formed that it is readily adapted to use in replacing worn rubber heels on shoes of different sizes so that the repairman is no longer 10 under the necessity to carry a full range of sizes of repair heels.

Another important object of my invention is to provide a combination heel of the character indicated wherein the nailing holes are so located that the heel may be immediately nailed in place on the heel of the shoe and the installation thereof completed simply by trimming the heel down to the particular size then required.

Other important objects of my invention will 20 be apparent from a reading of the following description taken in connection with the drawing, wherein for purposes of illustration I have shown a preferred embodiment of my invention.

In the drawing:—

25 Figure 1 is a plan view of a combination repair heel in accordance with the present invention.

Figure 2 is a plan view of a repair heel secured from utilization of the combination heel shown in Figure 1 by trimming off the upper and lower 30 projections appearing in Figure 1, the repair heel being of the maximum size, say size 9.

Figure 3 is a plan view of a small repair heel secured by utilization of the combination heel and representing a size "00" repair heel achieved 35 by trimming of the combination heel.

Figure 4 is a plan view of another size "00" repair heel achieved by utilization of the combination heel shown in Figure 1.

40 Figure 5 is a longitudinal sectional view taken through Figure 1 approximately on the line 5—5 and showing the convex curvature of the combination heel.

Ordinarily the shoe repairman must carry a full range of sizes of repair heels and in his repair 45 work there is usually an irregular consumption of certain sizes, so that the repairman has frequently on hand a relatively large stock of inactive sizes which after a certain length of time become aged and unfit for use, and represent unproductive investment. In addition to the foregoing considerations, it will be recognized that because of the necessity to purchase the heels in relatively large lots, in a complete range or sizes, usually without any limitation or selection 50 as to size ranges, the repairman is required to

invest an unnecessarily large amount of money to maintain a proper stock of repair heels. It is obvious that by eliminating the necessity for the repairman to keep on hand an unwieldy and unproductive stock, and enabling the repairman to purchase a relatively smaller and less expensive amount of heel replacements, as is provided for in the present invention, the expense to the repairman is reduced initially and also in the long run by reducing the amount of unproductive 10 stock, since in purchasing a supply of the heels of the present invention a repairman is required only to buy a supply of one "size" which is capable of being worked into any of the desired sizes by a simple operation already known to the trade. 15

With these considerations in mind, reference is made to the drawing, and particularly to Figure 1 thereof wherein the combination repair heel is generally designated 5 and comprises a body 6 of conventional thickness and conventional replacement heel material and whose main outline is in the shape and form of the largest required size of heel replacement or repair heel, changed only by the projection beyond the rear thereof of a heel portion 8 corresponding in contour and 25 size to a smaller sized replacement heel, and further altered in its front or forward edge by a projection 9 corresponding in outline and size to the fore portion of still another size of repair heel. It is evident that by trimming off the 30 projections 8 and 9 the largest size repair heel illustrated in Figure 2 of the drawing is quickly and easily achieved.

Within the periphery of the largest size heel 7 is an indicating line 10 which follows substantially the contour of the largest size heel 7 but is spaced inwardly therefrom to define the outline of the next smaller size heel, and spaced inwardly from this line 10 is the line 11 which defines the outline of the next smaller size heel. Both of 40 these smaller size heels 10 and 11 are achieved by trimming down the largest size heel 7 in a well known manner.

Merging with the projection 8 and the peripheral limits thereof is the line 12 which defines the 45 balance of a next smaller repair heel, achieved by trimming away the extraneous portions of the combination heel body, and below the heel line 12 is the line 13 which defines the same size of repair heel as the line 12 does, both ends of 50 this line meeting the periphery of the projection 9.

Of great importance is the manner in which the series of attaching nail receiving holes 14 and the series of attaching nail receiving holes 15 are 55

located in the heel body 6. The series 14 is located in a centralized position near the rear of the heel body and in such a position that they come in the proper places within the outline of the repair heel form 12, and the series 15 is located for similar reasons within the outline 13. It will also be observed that the series 14 and the series 15 are so located within the boundaries of the repair heel forms 7, 10 and 11 that they are in the proper position not only for nailing and attaching the heel forms 12 and 13 and any other desired smaller size repair heel, but also the heel forms 7, 10 and 11. These arrangements enable the repairman to take the combination repair heel 5, select the heel outline and register the heel outline with the heel of the shoe and then to insert and drive home the attaching nails and follow this operation by the trimming of the heel to shape. It is obvious that where either the heel form 12 or the heel form 13 has been used in the repair of a shoe, the heel body 5 may be retained as a means of supplying a heel form 12 or 13 as the case may be in another shoe repair operation.

Although I have shown and described herein the preferred embodiment of my invention, it is to be definitely understood that I do not desire to limit the application of the invention thereto, and any change or changes may be made in the structure and arrangement of the parts, within the spirit of the invention and the scope of the subjoined claims.

Having described the invention, what is claimed as new is:—

1. A combination repair heel of the character described, comprising a body having a desired cross section, the major portion of the periphery of said body conforming to the size and shape of the largest repair heel form wanted, the remaining portions of the periphery of the body including projections defining portions of smaller heel forms definable by trimming away parts of the heel body.

2. A combination repair heel of the character described, comprising a body having a desired cross section, the major portion of the periphery of said body conforming to the size and shape of the largest repair heel form wanted, the remaining portions of the periphery of the body including projections defining portions of smaller heel forms definable by trimming away parts of the heel body, each of the heel forms resident in said heel body being pierced by a series of attaching nail receiving holes.

3. A combination repair heel of the character described, comprising a body having a desired cross section, the major portion of the periphery of said body conforming to the size and shape of the largest repair heel form wanted, the remaining portions of the periphery of the body including projections defining portions of smaller heel forms definable by trimming away parts of the heel body, a side of said heel body containing markings defining sizes of heel forms smaller than that defined by the major outline for the largest size of repair heel, some of said outlines conforming to and merging into said projections.

SILVIO NENNI.
